BY

ATTORNEY

UNITED STATES PATENT OFFICE.

JOHN S. BRENNAN, OF MILWAUKEE, WISCONSIN.

OIL-BURNER.

1,315,361.

Specification of Letters Patent. Patented Sept. 9, 1919.

Application filed March 25, 1919. Serial No. 284,946.

To all whom it may concern:

Be it known that I, JOHN S. BRENNAN, a citizen of the United States, and resident of Milwaukee, in the county of Milwaukee and State of Wisconsin, have invented certain new and useful Improvements in Oil-Burners; and I do hereby declare that the following is a full, clear, and exact description thereof.

10 My invention relates to new and useful improvements in oil burner stoves, more particularly of the so-called "wickless" type shown in application for patent of Robert Perlick filed September 25, 1918, Serial No. 15 255,677 and comprising, with respect to each burner head, a non-combustible capillary member movable vertically to vary the amount of oil supplied therethrough in conjunction with a constant level source of oil 20 supply, a burner drum being disposed above and normally movable with this capillary member, but separable therefrom to permit lighting of the burner.

It is in general the object of my invention 25 to strengthen and otherwise improve the structure and to increase the efficiency of devices of this character.

In the operation of lighting the burner, it is necessary to lower the same to procure 30 a maximum impregnation of the capillary member of the burner head and a consequent free supply of oil. The burner drum has heretofore been raised and lowered manually to expose the burner head for lighting. 35 It has been found that, in this manual operation of separating the drum from the burner head, there exists in practice a liability for the operator to neglect raising the burner head to burning position after ignition, thus 40 maintaining an excess supply of oil resulting in a smoky and unsatisfactory operation, which reacts unfavorably on the general popularity of stoves of this character, despite the fact that it is due to the carelessness 45 of the operator.

It is therefore an important object of my invention to provide an arrangement wherein in the liability of careless and incomplete operation of the burner with respect to 50 lighting the same is lessened, thus safeguarding the operation of the stove, and it is more particularly my object to provide an arrangement for automatically procuring a spaced relation of the burner drum and

burner head when the burner head is lowered 55 to igniting position, and for automatically procuring reengagement of the burner head and drum when the head is raised to its proper burning position. Thus, when the burner head is lighted, open flames occur until the 60 burner head is raised from igniting to burning position to close the space between the head and the drum, and the occurrence of such open flames would thus practically compel the operator to raise the burner head. 65

A further object resides in the provision of an arrangement for insuring proper seating engagement of the burner drum on the burner head trough, whereby mutilation of the capillary burner member is prevented. 70

A still further object resides in the provision of an improved mounting for the burner drum wherein a support is afforded therefor additional to the normal support afforded by the burner head trough. 75

With the above and other objects and advantages in view, which will be apparent as the description proceeds, my invention resides in the novel features of construction, combination and arrangement of parts, as 80 will be hereinafter more particularly described and defined by the appended claims.

In the accompanying drawings:

Figure 1 is a view, partly in side elevation and partly in vertical section, of a burner 85 unit embodying my invention.

Fig. 2 is a similar view, looking toward the back of the burner.

Referring now more particularly to the accompanying drawings, there is shown a 90 burner drum of conventional nature comprising the outer cylindrical wall 5 and concentric foraminous inner walls 6 and 7 adapted to seat on the burner head and to receive the annular capillary member 8 95 therebetween, this capillary member being formed of the usual non-combustible material and seating in the burner head trough 9, the upper portions of the walls of the trough being offset to form seating shoulders 10 for 100 the drum walls 6 and 7, and it is noted that the offset portions of the trough walls are inclined whereby to guide the burner walls to proper seating position as the burner drum is lowered. The burner trough is supplied with oil and is supported by a depending stem 11 which is telescopically slidable 105 in a supply pipe branch 12 upstanding from

the main supply pipe 13, which as is common in stoves of this character, extends horizontally throughout the stove and is fed from a suitable constant level reservoir, the 5 level of oil thus supplied to the burner head being indicated by the line Y—Y of Figs. 1 and 2. The usual packing gland 14 is provided at the juncture of the stem and supply branch, the cap of said gland having a 10 wrench 15 associated therewith whereby it may be tightened from time to time.

As in the aforementioned patent, the mechanism for raising and lowering the burner head to control the feed of oil 15 through the capillary annulus includes a bracket formed of a single plate of metal intermediately bent to form a horizontally extending arm 16 through which the branch pipe 12 is passed, and a vertically extending arm 17 having its lower portion bent to also receive the branch pipe 12 and to seat on the attaching bead 18 of said branch pipe, the extremity of the arm 17 being continued below the main supply pipe 13. A strip 19 20 is secured to this lower extremity of the arm 17 by a bolt 20, and said strip is also secured by a bolt 21 to the arm adjacent its bend whereby to firmly clamp the arm against the main supply pipe and prevent looseness of 25 parts. The horizontal arm 16 of the bracket is also held against looseness by an arched plate 23 tensioned by a bolt 24 passed therethrough and through the arm, one end of 30 said plate engaging the juncture of the arm 35 and the branch pipe. The outer portion of the horizontal bracket arm 16 is supported by a brace rod 25 having its lower end mounted on the bolt 20 and having its upper end mounted on a bolt 26 passed through 40 the down-turned outer end of the bracket arm and through a dial plate 27 which is thus secured to the bracket arm. An exceedingly strong bracket structure is thus provided having all of its parts firmly held 45 against looseness.

The downwardly turned portion of the horizontal bracket arm 16 forms a journal for the forward end of an operating shaft 28 which has a second journal in the upper 50 portion of the vertical bracket arm 17, and immediately rearwardly of this bracket arm the shaft is flattened for rigid securement to one end portion of the crank arm 29, said end portion having its extremity bent inwardly at 30 whereby to form a stop engageable with the bracket to limit swinging movement of the crank arm, the crank arm being shown in intermediate position in 55 Fig. 2. A link 31 has its lower end pivoted 60 to the other end of the crank arm and has its upper end inwardly offset and pivoted at 32 to the burner head through 9 adjacent its juncture with the stem 8.

Thus, rotation of the shaft 28 will raise 65 and lower the burner head, and this rota-

tion of the shaft is effected by a handle plate 33 secured to the forward end of the shaft and extending obliquely with respect thereto, the inner end portion of this handle plate forming a pointer coöperating with the dial 70 plate 17 to indicate the various positions of the burner head as shown more specifically in the aforementioned patent.

To automatically procure spaced relation of the burner drum and burner head when 75 the head is lowered to igniting position, and at the same time to provide additional support and centering means for the burner drum, a vertical rod 34 is provided concentrically of the burner head and drum, said 80 rod having its lower end offset and secured at 35 to the back of the vertical bracket arm 17. This rod is passed through a sleeve 36 carried by and depending from a foraminous plate 37 extending across the upper portion of the burner head, and the upper end of the rod is engaged in a socket sleeve 38 carried by a foraminous plate 39 carried by the lower portion of the inner drum wall 6. The rod extends to such height as to engage 90 the end of the socket sleeve 38 at the normal limit of downward movement of the burner head and drum in burning position. Hence, as the burner head moves farther downward to igniting position, the burner drum will 95 be held against movement and thus the desired spaced relation of the head and drum will be procured to permit the insertion of a match therebetween for lighting the burner head. As heretofore stated, it has 100 been heretofore customary to raise and lower the drum manually in lighting the burner and practice has demonstrated a liability of the operator to neglect to raise the burner head from lighting to burning position, thus 105 resulting in a smoky and unsatisfactory operation. The present arrangement, in addition to increasing the convenience of operation of the stove, practically insures a proper operation since the occurrence of free flames 110 between the burner head and drum after lighting would make such active impression upon the mind of the operator as to insure the raising of the burner head from lighting position and consequently house the 115 flames within the burner drum. The rod 34, by its engagement in the sleeve 36 of the burner head, also holds the burner head against tilting movement on the stem 8. The rod further serves to facilitate proper 120 seating of the burner drum in a centered position, by its engagement with the central portion of the drum, to prevent possible mutilation of the capillary member of the burner head, which becomes somewhat brittle upon continuous use.

While I have shown and described a preferred embodiment of my invention, it will be appreciated that various changes and modification of structure may be employed 125

within the scope of the appended claims, without departing in any manner from the spirit of my invention.

What is claimed is:

- 5 1. In a burner of the class described, a vertically movable burner head, a burner drum normally movable with the burner head, and means for automatically procuring spaced relation of the burner head and
  - 10 drum upon movement of the burner head downwardly past a predetermined limit.
  - 15 2. In a burner of the class described, a support, a vertically movable burner head, a burner drum normally movable with the head, and stationary means carried by the support and engageable with the burner drum for limiting downward movement of the burner drum upon corresponding movement of the burner head.
  - 20 3. In a burner of the class described, a support, a burner head vertically movable above the support, a burner drum normally movable with the head, and a rod carried by the support and extending through the burner head and engageable with the drum to limit downward movement of the drum.
  - 25 4. In a burner of the class described, a support, a burner head, a supply tube for the burner head, means carried by the support and connected with the burner head for vertically moving the same, telescoping guide members carried by the support and burner head remote from the said supply tube and extending parallel to the direction
  - 30 of movement of the burner head to prevent tilting movement of the burner head.
  - 35 5. In a burner of the class described, a burner head movable vertically to procure burning and lighting positions thereof with respect to a constant level fuel supply line, a burner drum normally movable with the
  - 40
- burner head, and means operable upon movement of the burner head downwardly from burning to lighting position for preventing downward movement of the drum. 45
6. In a burner of the class described, a support, an annular head vertically movable above the support, a burner drum normally seating on the burner head and provided with a socket at its lower central portion, 50 and a rod carried by the support and extending through the burner head and engageable in said socket to limit downward movement of the drum.
  7. In a burner of the class described, a support, an annular burner head vertically movable above the support, an open end sleeve concentrically carried by the burner head, a rod extending from the support and passed through the sleeve, a burner drum 60 adapted to seat on the burner head, and a socket sleeve concentrically carried by the lower portion of the drum for receiving the upper end of the rod.
  8. A burner of the class described including a main supply pipe, a branch pipe upstanding therefrom, a burner trough, a depending stem carrying said trough and slideable in the branch pipe, a bracket carried by the branch pipe, an operating shaft journaled in the bracket, a crank arm secured on the shaft, a link pivotally connected with one end of said crank arm and with the burner trough, and the other end of said crank arm being laterally bent to form a 75 stop engageable with the bracket to limit pivotal movement of the crank arm. 70

In testimony that I claim the foregoing I have hereunto set my hand at Milwaukee in the county of Milwaukee, and State of Wisconsin. 80
